UNITED STATES PATENT OFFICE.

GEORGE THOM, OF WASHINGTON, DISTRICT OF COLUMBIA, ASSIGNOR OF ONE-HALF TO SAMUEL THOM, OF WASHINGTON, DISTRICT OF COLUMBIA.

PACKING DEVICE.

SPECIFICATION forming part of Letters Patent No. 699,775, dated May 13, 1902.

Application filed January 7, 1902. Serial No. 88,763. (No model.)

To all whom it may concern:

Be it known that I, GEORGE THOM, a citizen of the United States, residing at Washington, in the District of Columbia, have invented 5 certain new and useful Improvements in Packing Devices, of which the following is a specification.

My invention is an apparatus for packing crackers, biscuits, or other like articles; and 10 my invention consists of a machine provided with means for bringing the articles in rows one article against the other, so that they can be readily transferred, and in a packer consisting of a trough and plunger, said trough 15 being provided with converging ends, whereby the rows of articles may be delivered together in proper order into boxes or bags placed upon said ends, as fully set forth hereinafter and as illustrated in the accompanying 20 drawings, in which—

Figure 1 is a plan view of my improved packing apparatus. Fig. 2 is a section on the line 2 2, Fig. 1. Fig. 3 is a section on the line 3 3, Fig. 1; Fig. 4, a section on the line 4 4, 25 Fig. 1; Fig. 5, a perspective view in part section, and Fig. 6 a view illustrating a modification. Figs. 2, 3, 4, 5, and 6 are drawn to a larger scale than Fig. 1.

A frame B is suitably supported upon legs 30 or standards C, and above the table, near the center of the same, is a shaker A, so suspended by links 16 that it can be reciprocated rapidly back and forth in any suitable manner. The shaker is inclined downward toward the forward end and is provided with a receiving-platform 1, upon which are deflectors 2, which serve to deflect toward the sides of the shaker, the rectangular blocks y representing biscuits or any other articles which it is desired to 35 pack. At the forward end of the shaker are parallel ribs or partitions 5 6, their ends all projecting over the forward end of the shaker, the ribs 6 being fixed in place and the ribs 5 having near the rear end grooves x, through 40 which extend pins 8, while the forward ends of these ribs or partitions project through slots in plates 7, pendent from a cross-piece 9. By so securing or supporting the alternate ribs 5 that they may have a slight back-and-forward motion under the influence of the 45 movements of the platform I prevent the articles y from jamming in between the ribs 5 and 6, as in case one of said articles should

enter at an angle and tend to remain in place the slight longitudinal movement of the adjacent rib would tend to displace it and cause it to assume a different position, so as to gradually slide forward between the ribs to the end of the shaker. The plates 7 are supported at such a distance beyond the end of the shaker 55 that as the articles reach this end they may assume an inclined position and fall downward between the partitions 12 on an inclined receiver D, and into the channels between said partitions extend plates 10, projecting downward from the forward end of the platform 1, so that as an article falls downward between the plates 7 and 10 and into one of the channels the forward movement of the plate 10 by contact with the article will tend to throw it 60 forward and against the other articles in the channel, which are thus gradually fed forward in substantially an upright position in contact 65 with each other. The attendant from time to time takes a series of the articles thus brought 70 together face to face and deposits a sufficient number of the same crosswise in the trough 19 of the packer E. The said packer consists of the said trough, constructed as hereinafter described, and a reciprocating plunger 20, 75 which as it moves in one direction pushes the mass of articles y forward toward the end of the trough. As shown, the trough has upright fixed sides 22, is open at the top, and near the delivering end the sides 22 are so 80 constructed as to converge slightly and yield for the passage of the mass of articles between them. The flexibility of the converging ends of the sides may be secured by making these ends thinner than the other side portions so as to spring outward beyond these side 85 portions, as illustrated in the construction shown in Fig. 6; but preferably this is secured by hinging the ends 25 to the rigid side portions by hinges 26, with arms 27 projecting rearward and pressed outward by springs 28, which tend to throw the converging side portions 25 toward each other. The bottom 30 of the trough extends forward as far as the ends of the side portions, and preferably 90 there is a cap-piece 31 hinged to a cross-bar 32 and tending to fall toward the bottom at its forward end to the position shown in Fig. 5. A mass of the articles having been placed 95 in front of the plunger 20, the latter moves outward toward the end of the trough in the 100 105

direction of its arrow and carries the articles between the converging ends 25 25 and below the cap 31, the said ends and cap yielding for the passage and tending to hold the articles properly in position in respect to each other, so that they will be introduced properly into a bag or box which has been placed upon the end of the packer in the position indicated by dotted lines X, Fig. 5. As soon as the mass of articles has thus been transferred from the trough to the box the plunger 20 moves back to a position to receive another mass of articles in front of it and the box X is removed and another is put in its place and the articles deposited therein in like manner, or if the box or bag is of sufficient size a second layer of articles is deposited in it in contact with the first.

As shown, the packer E and plunger are double-ended—that is, at each end the sides are flexible and converge, so that they may be spread outward as the articles pass between them, and at each end there is a hinged cap 31, and, if desired, in order to adapt the machine to packages of different sizes the trough may be made in two sections, the bottom portion of one section overlapping the other, as indicated in Fig. 5, with a binding-screw 35, whereby the parts may be secured after adjustment. As shown, there are two packers, one at each side of the receiver D, and each of the packers is double-ended, so that four attendants may operate in connection with a single shaker and single receiver. By this means the bags or boxes may be filled with great rapidity. In view of these rapid operations the attendants cannot give any attention to the disposal of the boxes after they are filled, and I therefore provide conveyers F in the form of continuous straps passing around rollers 39 and extending below the ends of the packers, so that the attendants as soon as a box or bag receives its contents can draw the box from the end of the packer and place it without further manipulation directly upon the conveyer, by means of which it is conveyed to one end of the machine, where it is taken off, and the box is closed or the bag is folded down upon the articles within the same.

It will be evident that any suitable form of conveyer other than that shown may be employed and also that the parts above described may be constructed in different ways without departing from the main features of my invention. It will also be seen that any suitable means may be employed for vibrating the shaker and for reciprocating the plunger. As shown, there is a double plunger in each packer, and this is connected by a link 40 to a vibrating arm 41, to which motion is imparted from a suitable eccentric 42 by means of a rod 43, and the shaker is vibrated from a rotating crank-wheel 45, to which rotation is imparted by means of a belt 46, driven from a shaft carrying the eccentric 42.

Without limiting myself to the precise construction and arrangement of parts shown, I claim—

1. The shaker provided with the receiving platform, and with partitions extending beyond the platform capable of limited longitudinal play independently of the movements of the platform, substantially as set forth. 70

2. The shaker provided with the receiving platform, and with partitions extending beyond the platform, the alternate partitions capable of limited longitudinal play independently of the movement of the platform, substantially as set forth. 75

3. The combination of the reciprocating platform having partitions and discharge-openings between the partitions, transverse blades in front and rear of said openings, and a channeled receiver into the channels of 85 which the rear blades project, substantially as set forth.

4. The reciprocating platform with discharge-openings and blades extending downward in front and at the rear of said openings, combined with a receiver having channels into which the rear blades project, substantially as set forth. 90

5. The combination in a packing-machine, of a reciprocating plunger and a trough for receiving the articles to be packed adapted at the end to enter the packing box or receptacle and provided at said end with yielding sides, substantially as set forth. 95

6. The combination of the reciprocating plunger and a trough having yielding sides and a yielding cap, substantially as set forth. 100

7. The trough having a rigid bottom, sides adapted to yield near the end of the trough for the passage of articles between them, a 105 cap pivoted between the sides, and a plunger reciprocating in the trough, substantially as set forth.

8. The combination in a packing-machine, of a trough having yielding side portions at 110 each end and a double-ended plunger, and means for reciprocating it in the trough, substantially as set forth.

9. The combination with a reciprocating plunger, of a trough adapted at the end to enter the packing box or receptacle and its sides having the terminal portions pivoted to swing laterally, and springs for carrying the pivoted portions inward, substantially as set forth. 115

10. The combination with a reciprocating plunger, of a trough, sides having the terminal portions pivoted to swing laterally, springs for carrying the pivoted portions inward, and a cap pivoted between the sides, substantially as set forth. 120

In testimony whereof I have signed my name to this specification in the presence of two subscribing witnesses.

GEORGE THOM.
